SNOW SHOE

Alexander C. H. Weiss, Deerfield Beach, Fla., assignor to the United States of America as represented by the Secretary of the Army

Application August 2, 1956, Serial No. 42,494

Term of patent 14 years

(Cl. D34—14)

(Granted under Title 35, U. S. Code (1952), sec. 266)

The invention described herein may be manufactured and used by or for the Government for governmental purposes without the payment to me of any royalty thereon.

I claim:

The ornamental design for a snow shoe, substantially as shown.
